UNITED STATES PATENT OFFICE.

BERNARD A. KEARNS, OF CINCINNATI, OHIO, ASSIGNOR TO CINCINNATI GRINDERS INCORPORATED, OF CINCINNATI, OHIO, A CORPORATION OF OHIO.

GRINDING MACHINERY.

Application filed May 31, 1927. Serial No. 195,187.

This invention relates to improvements in grinding machinery and has particular reference to novel and improved mechanism for steadyng the work piece during grinding.

5 Prior to the present invention it has been customary in the grinding of work pieces in cylindrical grinders to support the work as between headstock and tailstock members, and to brace the work during grinding by 10 one or more steady rests or work contacting members, operating independently of each other in direct engagement with the work. A difficulty has here been experienced, however, due to the fact that the grinding constantly decreases the diameter of the work 15 piece being acted upon. It is therefore necessary to advance the rest toward the work to compensate for this reduction in diameter and this has been a delicate operation to perform, due to the fact that if sufficient pressure is not applied to the work at a point 20 substantially opposite the grinding wheel, the grinding wheel tends to spring the work away, so that less stock will be centrally than 25 terminally removed from the work piece. On the other hand, if the steady rest be set up too tight the rest tends to spring the work in toward the grinding wheel more at the center than the ends, with the result that 30 more stock is centrally removed and the piece again is not of true cylindrical form.

It is therefore one of the purposes of the present invention to provide an improved steady rest mechanism which may be adjusted 35 to apply a proper supporting pressure to the work piece, but in which the application of pressure will be through a compensating mechanism tending to keep a constant contact between work piece and rest and at the 40 same time a balanced pressure condition, preventing inward springing of the work.

A further object of the present invention is the provision of a steady rest mechanism which may be either manually or automatically 45 controlled to apply a continuous pressure to a work piece.

An additional object of the invention is the provision of a mechanism which will satisfactorily support a work piece against both 50 the feeding pressure and the cut pressure of grinding wheel with a balanced force substantially equally distributed between the work engaging members.

Another object of the invention is the pro-

vision of an adjustable mechanism whereby 55 work pieces of different sizes or diameters may be satisfactorily engaged or supported without varying the position or action of movement of the actuating means therefor.

Other objects and advantages of the present invention should be readily apparent by 60 reference to the following specification taken in connection with the accompanying drawings, and it will be understood that I may 65 make any modifications in the specific structural details hereinafter disclosed within the scope of the appended claims, without departing from or exceeding the spirit of the invention.

Figure 1 is a side elevation of my improved 70 steady rest in position on a grinding machine.

Figure 2 is a central sectional view therethrough.

Figure 3 is a view in elevation, showing an 75 automatic control mechanism therefor.

Figure 4 is a vertical section through the 80 automatic control mechanism.

Figure 5 is a section through a steady rest 85 mechanism having a greater range of adjustment than that shown in Figure 2.

Figure 6 is a plan view of a grinding machine with my improvements applied thereto, and

Figure 7 is a vertical section taken as on 90 the line 7—7 of Figure 6.

In the drawings in which similar characters of reference are employed to denote corresponding parts throughout the several views, the letter A designates the work supporting table of a grinding machine which is 95 disposed in opposition to the grinding wheel B. C is a work piece supported in opposition to the grinding wheel in any conventional manner. The supports for the work piece as shown may for example comprise the usual grinder headstock D and tailstock member E.

The steady rest mechanism thus is designed 100 to brace and support the portion of work in opposition to the grinding wheel B to take up both the thrust of feed and the cut thrust of the grinding wheel. It comprises a base or bracket portion 10 secured to the table as by the clamp 11 and screw 12. This member is provided with the guideways 13 on which are slidably mounted the lower steady rest 105 14 and outer steady rest block 15. Member 14 carries a steady rest shoe or blade 16 for engagement with the work below the axis there-

of and on the same side of its axis as the grinding wheel itself is disposed. Member 15 on the contrary supports a roller 17 rotatable as on spindle 18 and engaging the work at substantially a diagonally opposite point from the point of engagement of the grinding wheel therewith.

It will be noted that both of these members are supported for sliding movement on the main base or bracket 10, while to limit said movement the bracket is provided with the lug 19 projecting intermediate parts 14 and 15. This lug serves as an abutment for springs 20 and 21 contained in sockets 22 and 23 respectively of the members 14 and 15. These compression springs therefore serve to urge said last mentioned member in a direction away from each other and from the intermediate lug 19. At the same time they resist general movement of the work steady- 20 ing parts when the same are positioned to function in unison.

To obtain cooperative functioning of the work contacting members 16 and 17 there is pivoted to ear 24 on block 15 an actuating lever 25, which may be either manually or automatically actuated. This lever in either event has a yoke portion as at 26, receiving adjusting rod 27. The other end of this rod is engaged in guide lug 28 depending from member 14, the lug and guide rod being contained in the groove 29 of member 10, intermediate the ways 13.

At its outer end the rod 27 is threaded to receive the adjusting nuts 30. These nuts by back and forth adjustment serve to impart an in and out movement to the member 14 with respect to the lever 25 and thus with respect to the member 17, carrying this lever. In the form of invention shown in Figures 1 and 2 the pivot ear 24 has an extension as at 31 to which is pivoted the handle 32 having a cam head 33 for cooperation with lever 25. Consequently, on depression or downward rocking of handle 32 the cam will force inwardly or toward the grinding wheel the upper end of lever 25. This in rocking will tend to shift rod 27 and consequently member 14 outwardly, until shoe 16 is brought into contact with work piece C. Continuation of movement or the same movement will cause a balanced action between members 14 and 15, in that the fulcra 26 and 33' are jointly movable in opposite directions depending on whether member 14 or 15 meets with greater resistance to movement. The tightening action of the cam lever therefore tends to shift both of these members and press the contact shoes 16 and 17 with equal pressure against substantially opposite sides of the work piece C. Consequently, these members are in effect clamped against the work piece, the springs 20 and 21 being compressed as this action takes place. The general friction of the parts combined with the resistance of

the springs tends to hold the steady rest mechanism as an entirety against motion, although if sufficient resistance be encountered it is capable of a yielding action with the work piece and subsequent return to its initial position. 70

From this it will be seen that in effect the present mechanism is a floating steadyng device bracing the work positively against downward springing movement through the combined action of members 16 and 17 and 75 holding it against springing movement away from the grinding wheel to the extent of frictional resistance and resistance of spring 20, the latter forcing itself into its normal balanced condition when the undue pressure is 80 withdrawn.

It will be understood with the mechanism just described that the downward swinging of handle 32 may be effected either as a continuous manual proposition or that a spring 85 34 or weight may be utilized to supply a continuing pressure to take up the slack or play as the diameter of the work piece decreases.

In Figures 3 and 4 have been illustrated a slight modification of this, in which use is made of a controlling cylinder and piston for movement of the lever 25, the structure of the parts being otherwise the same. In this form the lever for clarity has been designated as 35, its structure being the same as lever 25, except that it is located in a depending position in place of an upstanding one. At its lower end it is formed with a pin portion 36, depending through a slot in the wall of cylinder 38, carried by bracket 39, depending from member 15. This pin fits within the diagonal slot 40 of the double end piston member 41 which is slideable in the cylinder and held against rotation as by screw 42, engaged in groove 43 of the piston. This piston may be actuated as by compressed air or other fluid supplied from pressure line 44 to valve 45. This valve may be set to connect either line 46 or 47 with the pressure line 44 and at the same time to connect the opposite line with the exhaust port 48. The valve has a manually actuatable handle portion 49. In use, pressure is introduced through line 44, valve 45 and line 46 to the right hand end of the cylinder, tending to shift the piston to the left. As the piston is so shifted, slot 40 will tend to cam outwardly pin 36 and thus to rock lever 35. This action draws rod 27 outward and pushes member 15 inward, so that the parts are brought into proper clamping supporting engagement with the work. Inasmuch as the pressure may be kept constant irrespective of the movement of the piston, this means that a continuous even pressure will be exerted against lever 35, tending to maintain the two work steadyng shoes in proper work engaging position so long as the line 46 is coupled with the pressure line. If desired, to limit the possible inward forcing 120 of the work steadyng members, use may be 125 130

made of the abutment screw 50 adapted to contact with the end of the piston 41 limiting its movement in an actuating direction.

While the parts are thus operating, the position of the valve will be as shown in Figure 4, it being understood that when the valve is reversed, line 47 will be connected with pressure line 44, causing a reversal of the piston, while the compressed air or the like therein is allowed to escape through port 48.

In Figure 5 has been shown a slightly modified form of the invention in which in addition to the adjustment of member 14, possible due to the threading of rod 27 and the nuts 30 which serve therefor initially to vary the position of the member 14 and consequently the final effective position of both members, the member 55 has been provided, corresponding to member 15, with the difference that it is made in two parts, the basal portion 55 and the supplemental slide section 56, carrying a roller 57 corresponding to roller 17. This slide, however, is adjustable relative to the support portion 55 as by the screw 58, so that it is capable of in and out initial movement relative to the work piece. This structure makes it possible to accommodate a greater variety of sizes of work pieces with a single mechanism, than were possible if all such adjustments had to be made merely by shifting of position of the nuts 30. In addition, longer springs 60 and 61 have been employed to take care of greater possible range of floating movement of the device as an entirety or of individual adjustment of the member 14 as may be desired.

From the foregoing description taken in connection with the accompanying drawings, the construction and advantages of the present improved steady rest mechanism should be readily apparent, and it will be seen that there has been provided a mechanism in which a lower contact shoe and a lateral contact shoe or work bracing member are so interconnected that the two parts will exert substantially equal and balanced pressure on the work pieces and so that the action of bringing in the lateral rest will be a pressure exerted not positively in a direction opposing the grinding wheel, but yieldingly opposing the grinding wheel through the use of interposed springs 20 or 60, combined with a take-up of the general pressure against the work itself, so that the member 17 may be firmly held up against the work, without an undue springing thereof as would take place were a resisting pressure not applied through member 16. It will further be seen that by the mechanism provided this pressure may be kept substantially continuous and constant during any desired stock removal from the work piece, so that the work piece at all times will be properly supported against either vertical or lateral springing during grinding.

In Figure 6 the grinding machine illus-

trated is of the plunge cut type in which there is a continuous direct relative feeding movement of the grinding wheel B and the work, so that there is a continuous even pressure of the work toward the steady rest.

For most efficient grinding the steady rest here illustrated is shown as provided with a special attaching clamp 62 permitting of an in and out movement of the steady rest mechanism with respect to the supporting table A. 70 This may be conveniently effected as by the swivel or adjusting screw 63 carried by the steady rest bracket and engaged in the bed. This movement shifts the steady rest as an entirety on the inclined upper face 64 of the table, thus raising or lowering it with respect to the center line of the grinding wheel to best accommodate differing work pieces.

In addition, to form the work rest, slide 65 has journalled therein the cylindrical rod 66 slotted to receive the work rest blade 67, which may be shifted through slot 68 of member 65. This varies the point of engagement of the angle top 69 of the work rest with the work. The adjustment may be suitably effected as by formation of a pinion portion 70 on member 66, meshing with worm 71, carried by support 65. A knurled head 72 facilitates rotation of the worm and thus adjustment of the position of the work rest blade 69. Similarly, there is opposed to the work rest the work engaging roller 17 journalled in bracket 73 which is vertically adjustable as by screw 74 with respect to the block or column 75. This member 75 is mounted for in and out adjustment with respect to the main support 76 of the work engaging roller as by screw 77. By reference to this figure it will therefore be seen that the customary actuating lever 25 may be suitably operated as in the other forms of the invention to force members 17 and 69 respectively one toward the other for proper work engagement. To perfect the engaging points of these members with the work as for grinding of different materials, work pieces having unround condition or the like, the angle of the rest itself may be varied, changing its point of engagement with the periphery of the work, and the in and out position and vertical position of contact roll 17 may also be controlled. Incidentally, the position of the fixture as an entirety as respects the horizontal plane of the grinding wheel may be altered by rotation of screw 63.

These features are of particular importance in connection with the infeed or plunge cut method of grinding as accomplished by the machine shown in Figure 6, for example.

In the infeed or plunge cut method of grinding the grinding wheel and work being ground are brought into contact through either the infeed movement of the grinding wheel unit or that of the work sustaining unit, ordinarily without relative traversing movement of the work and grinding wheel.

When work is placed between centers to be ground, it is generally assumed that the centers do not spring away from the grinding wheel when the pressures build up from the action of the grinding wheel. Springage of the work centers does occur and prevails until the infeed rate ceases, after which the centers tend to resume their normal position, creating an observable condition, known as the "sparkling out" interval. This interval length is determined by the stability of the centers and other structural and operating conditions of the grinding machine. The work itself on the centers tends to spring away from the grinding wheel, and tends to set up or build up vibration, that manifests itself in the finish secured on the work, and also tends to break down the grinding wheel, with a resulting tapering or out of round condition of the work.

The backrest will be utilized to spring the work in beyond the normal alignment produced by the dead centers. This springage can be progressive thru the stock removal period or loaded up to a stop on the backrest according to the nature of the work. As the grinding progresses, and eventually the infeed ceases, the backrest ceases to function, the centers tend to resume their normal alignment and the work takes a final rounding up on dead centers. The higher infeed rate that will be allowable when using the backrest will give higher production, and the proper synchronizing of backrest stop and infeed stop will cause a proper resumption of dead center alignment, resulting in a much shorter "sparkling out" interval and better rounding up of the work.

One of the prime considerations in producing most accurate work in accordance with the foregoing is that there be a proper angular relationship between the radial lines drawn perpendicular to the points of contact of the grinding wheel, the roller back rest and the blade rest. The intersection of these radial lines approximates the center of the work, and the angular relation that exists between them has a material influence on the introduction or elimination of chatter on the rounding up of work and on light lines on the finished work. The most desirable condition is that in which a maximum number of revolutions of work will be required before the cycle of contacts repeat.

With the structure just described these points may be accurately determined both by in and out and vertical adjustment of the roller back rest 17 and by varying the angle of work rest blade 67 and thus its exact position of contact with the work as respects the other two contacts.

By these several adjustments most accurate and satisfactory work can be attained.

I claim:

1. A steady rest mechanism, including a

supporting member, a steady rest shoe carried thereby having an angle top work engaging surface for line contact with the work at one side of the axis thereof, and a contact roller also carried thereby and positioned to engage the work at the opposite side of the axis thereof.

2. A steady rest mechanism, including a support, a pair of slides carried thereby, work engaging members on the slides, connections between the slides for adjusting their position with respect to each other, and automatic means for effecting such adjustment.

3. A steady rest mechanism, including a support, a pair of slides carried thereby, work engaging members on the slides, connections between the slides for adjusting their position with respect to each other, automatic means for effecting such adjustment, and additional manually actuatable means for varying the relative position of the work engaging members.

4. A mechanism of the character described, including a work engaging shoe and a spaced work engaging roller, and means for jointly urging said parts against opposite sides of a work piece whereby the part will maintain constant contact with the work piece during the removal of stock therefrom, and means sub-tending the work engaging shoe for rigidly steadyng the same against displacement in a direction transverse to the work engaging urge therof.

5. A device of the character described, including a supporting portion, a pair of slides mounted thereon, and movable relative thereto, and to each other, means interconnecting the slides for relatively shifting the same, and resilient means for resisting joint movement of the slides with respect to the support.

6. A mechanism of the character described, including a supporting portion, a pair of slides mounted thereon for joint or independent movement, a lever pivoted to one of the slides, connections between the lever and the other of the slides, means for rocking the lever to adjust the relative position of the slides and means for adjusting the effective connection between the lever and said other slide.

7. A mechanism of the character described, including a supporting portion, a pair of slides mounted thereon for joint or independent movement, a lever pivoted to one of the slides, connections between the lever and the other of the slides, and automatic means for rocking the lever to adjust the relative position of the slides and means for resisting bodily movement of the slide members and actuating lever as a unitary entity.

8. A steady rest mechanism, including a support, and a pair of opposed relatively adjustable work engaging members carried thereby, and a single means for constantly

urging the members toward each other with a constant pressure and means for relatively adjusting the effective distance between said work engaging members without variance in the pressure urge thereof.

9. A steady rest mechanism, including a support, a pair of opposed work engaging members movably mounted on the support and comprising a work rest blade for peripheral engagement with a work piece to support the same against the cut thrust of a grinding wheel and a cooperating roller for steadyng engagement of the work piece to resist the feed component of the grinding wheel thrust, adapted to engage opposite sides of a work piece, and means for jointly actuating the work engaging members one toward the other with a constant and uniform pressure, said means including shiftable connections between the members and a pressure actuated piston for shifting said connections.

10. A mechanism of the character described, including a support, a pair of spaced work engaging members carried thereby and adapted to receive a work piece therebetween, means supporting said members for independent movement relative to the support, interconnecting means for shifting the work engaging members toward each other to grip a work piece therebetween, and yieldable connections between the members and the support for resisting the joint floating movement of the members on the support.

11. A steady rest mechanism including a work supporting blade having an angled work engaging surface, and means for varying the angular relationship of the work and supporting surface of the blade.

12. A back rest of the character described, including a work rest blade and an opposed work engaging roller, and means for vertically and laterally adjusting one of said parts with respect to the other.

13. A back rest of the character described, including a work rest blade and an opposed work engaging roller, means for vertically and laterally adjusting one of said parts with respect to the other, and additional means for varying the angular relationship of said parts.

14. The combination with a grinding machine including a grinding wheel and a work supporting table, of a steady rest mechanism for application to the table including a bed portion having slide ways formed thereon, a pair of slide members carried by the ways and each provided with a work rest member one of which is designed to project intermediate the grinding wheel and axis of the work and the other at a point in substantially diametrical opposition to the grinding wheel, means for positively urging the two work rest members one toward the other to clamp the work piece therebetween where-

by the one rest will support the work against the cut pressure of the grinding wheel and will hold the other rest against the work in resistance to the feed pressure of said wheel, and means for yieldingly resisting movement of the combined work engaging members as a unit either toward or from the grinding wheel.

15. The combination with a grinding machine including a grinding wheel and a work supporting table, of a steady rest mechanism for application to the table including a bed portion having slide ways formed thereon, a pair of slide members carried by the ways and each provided with a work rest member one of which is designed to project intermediate the grinding wheel and axis of the work and the other at a point in substantially diametrical opposition to the grinding wheel, means for positively urging the two work rest members one toward the other to clamp the work piece therebetween whereby the one rest will support the work against the cut pressure of the grinding wheel and will hold the other rest against the work in resistance to the feed pressure of said wheel, means for yieldingly resisting movement of the combined work engaging members as a unit either toward or from the grinding wheel, the ways of said bed portion extending directly beneath the inner work engaging member to provide a positive and nonyielding support therefore in the direction of cut pressure.

16. The combination with a grinding machine including a grinding wheel for operation upon work and a work carrying table disposed in opposition thereto, of a steady rest bed member for application to the table having elongated guide ways extending transversely thereof, aligned slide members mounted on the guide ways and rigidly held thereby for in and out movement, means cooperating with the bed member for individually urging the work supports away from each other, said means determining the inoperative position of the slides with respect to the supporting bed, and a common means for urging the slides one toward the other to suitably engage and support a work piece.

17. The combination with a grinding machine including a grinding wheel for operation upon work and a work carrying table disposed in opposition thereto, of a steady rest bed member for application to the table having elongated guide ways extending transversely thereof, aligned slide members mounted on the guide ways and rigidly held thereby for in and out movement, means cooperating with the bed member for individually urging the work supports away from each other, said means determining the inoperative position of the slides with respect to the supporting bed, and a common means for urging the slides one toward the other to suitably engage and support a work piece,

and additional means for relatively adjusting the initial position of one work engaging member with respect to the other.

18. In combination with a grinding machine including a grinding wheel and a work supporting table disposed in opposition thereto, a steady rest mechanism for application to the table including a bed portion, a slide carried thereby and provided with a work rest blade disposed substantially at right angles to the sliding support therefore, a second slide carried by the bed, a work engaging roller carried by the second slide for cooperation with the work rest blade in engaging a work piece on the table, means for jointly urging the roller and blade toward each other to clamp a work piece in the trough therebetween and resilient means for steadyng the device as a unit in position on its bed, said means operated to individually urge the two work contacting members into

positions remote from the work on release of their joint actuator.

19. The combination with a grinding machine including a grinding wheel and a work supporting member disposed in opposition to the grinding wheel, of a steady rest mechanism including a work supporting blade adapted to be positioned adjacent the grinding wheel and a roller adapted to be positioned to engage the work at a point remote from the grinding wheel, said parts being arranged to form a two point contact trough for reception of the work, means for varying the effective width of the throat to correspondingly engage different diameters of work pieces thereon, and additional means for automatically varying the width of said throat to compensate for stock removal on a work piece disposed therewith.

In testimony whereof I affix my signature.
BERNARD A. KEARNS.
